REEL

Henry J. Hogue, Lakewood, Ohio, assignor of
one-third to Charles L. Wasmer and one-third
to John C. Wasmer, both of Lakewood, Ohio

Application April 14, 1937, Serial No. 136,856

3 Claims. (Cl. 242—128)

This invention relates to reels for bundles of rods or wire from which the rods or wire may be uncoiled and fed to another machine such as a straightener, a wire-drawing machine, or a 5 fabricating machine.

It is one of the objects of the invention to provide a reel, for the purpose specified, which is adapted to support one or more bundles from which the rods or wire may be uncoiled or drawn 10 without rotating the bundle.

A further object of the invention is to provide a reel of the type referred to in which the bundles are held against rotation while the stock is being withdrawn therefrom, so that the end 15 of another bundle may be welded to an end of the bundle on the reel and thus avoid the interruption of the operation of the machine to which the stock is fed that is necessary in the case of the reels now commonly used and on which the bundles rotate.

Other objects of the invention and the features of novelty will be apparent from the following description taken in connection with the accompanying drawings, in which

Fig. 1 is a side elevation of a reel embodying my invention and shown in its normal relation to the machine to which the stock is to be fed.

Fig. 2 is an enlarged elevation of the reel with certain parts broken away and other parts shown 30 in section.

Fig. 3 is an elevation of the delivery end of the reel.

Fig. 4 is an enlarged section of a fragment of Fig. 2, the section being taken on the line 4—4 of 35 Fig. 3.

Fig. 5 is an enlarged section on the line 5—5 of Fig. 3.

Fig. 6 is an enlarged fragment of Fig. 5, and also a section on the line 6—6 of Fig. 7.

Fig. 7 is a side elevation of the details illustrated in Fig. 6.

Referring to Fig. 1, 10 illustrates, more or less diagrammatically, a machine to which the stock, such as rods or wire, is to be fed and, depending 45 upon the use that is to be made of the stock, the machine 10 may be a straightener, a wire-drawing machine, or some form of fabricating machine in which the stock is worked up into some fabricated product. The reel, embodying 50 my invention, is illustrated at the right in Fig. 1 and consists mainly of a substantially circular frame 11 having a base 12 that is adapted to be secured to a floor or other suitable form of support. To the rear of the frame 11 is an angular 55 casting 13 that is adapted to be secured to the

floor or support. A plate 14 has its forward end secured to a ledge 15, on the frame 11, by a suitable number of bolts 16 and is upwardly inclined, as shown in Fig. 2, and has its rearward end secured on the casting 13. Bosses 17 are provided on the rearward side of the frame 11 and rails 18 have one end secured in these bosses and extend horizontally therefrom and then downwardly for connection to the casting 13, as indicated at 19.

The frame 11 has a relatively large central opening 20 therein, and spaced radially outward from this opening, on the forward side of the frame 11, is a flange 21 on which an annular plate 22 is secured by means of bolts 23. An annular recess 24 is thus formed around the central opening 20 and on the forward side of the frame 11. A circular plate 25 is arranged on the forward side of the frame 11 with its periphery extending into the recess 24 as will be seen 20 from Figs. 4 and 5. Radial slots 26 are formed in the outer edge of the plate 25, these slots being spaced at equal intervals around the plate 25 and having mounted therein short shafts 27, the ends of which are squared to fit the slots 26 so as to 25 prevent the shafts from rotating. A peripheral slot 28 is provided in the plate 25 and anti-friction bearings 29 are mounted on the shafts 27 and extend into the slot 28, as will be seen 30 from Figs. 5, 6 and 7.

The outer peripheral wall 30 of the recess 24 constitutes a track on which the anti-friction bearings 29 run so as to rotatably support the plate 25. Between the anti-friction bearings 29 the periphery of the plate 25 is provided with 35 the relatively large notches 31, and in each of these notches there is a radially extending stud 32, as shown in Fig. 4, and on each of these studs there is an anti-friction bearing 33 which is adapted to engage either of the walls 34 or 35 40 of the recess 24 and run thereon. In this manner the plate 25 is held against axial displacement, although free to rotate.

To seal the joint between the plate 25 and the inner periphery of the annular plate 22, the latter is counterbored on its inner side, as indicated at 36, and a felt ring 37, having a reinforcing band 38 on its interior, is mounted in this counterbore and secured therein by means of screws 39. Angle clips 40 are secured on the outer face 50 of the plate 22, by means of screws 41 and are also attached to the band 38 so as to assist in holding the latter in position.

At one point, adjacent its periphery, the plate 25 is provided with an opening 42 in which is 55

secured a bushing 43 having an opening 44 there-
in to permit the passage of the rod or wire stock
through the plate 25. The bushing 43 has a
flange 45 and this flange is secured to the plate
25 by means of bolts 46.

On the rearward side of the plate 25 there is a
central boss 47 and a shaft or spindle 48 is se-
cured in this boss and projects rearwardly from
the plate 25. A drum 49, of any suitable con-
struction, has its hub 50 mounted on the shaft
48 by means of anti-friction bearings 51 so that
the plate 25 will be free to rotate while the drum
49 remains stationary. The forward end of
the drum is arranged in slightly spaced relation
15 to the plate 25 as will be seen at 52 in Fig. 2.

The rails 18 are arranged on opposite sides of
the drum 49 and in the horizontal portion of
these rails, rearwardly of the drum 49, there are
notches 53 to receive a bar 54.

20 As shown in Fig. 1, one or more bundles of
rod or wire stock 55 may be supported on the
plate 14 and in position on the drum 49, and the
stock is conducted from the bundle closest to the
frame 11 and through the opening 44 to the
25 machine 10, as indicated at 56 in Fig. 1. As the
stock is drawn forward the bundles and the drum
49 remain stationary, but the plate 25 rotates
to uncoil the stock from the bundle. It will thus
be seen that the axis of the drum 49 extends in
30 the same general direction that the stock moves
from the reel. On account of the fact that
the bundles do not rotate while the stock is
being withdrawn therefrom it is possible, with a
reel made in accordance with my invention, to
35 position several bundles on the reel and to weld
the trailing end of the first bundle to the lead-
ing end of the second bundle and, if there is a
third bundle in position, the leading end of that
bundle may be welded to the trailing end of the
40 second bundle, and all of this may be done while
the stock is being uncoiled from the first bundle.
Thus it is possible, with my invention, to allow
the machine 10 to which the stock is fed, to oper-
ate continuously and without stopping the feed-
45 ing movement of the stock to either weld on the
end of another bundle or to start the leading end
of another bundle into the machine. The notches
53 and the bar 54 provide for the positioning of
extra bundles of stock so that as the stock is
50 withdrawn from the bundle or bundles on the
drum 49 the extra bundles may be moved for-
ward toward the frame 11 and by having sev-
eral of the notches 53 the bar 54 may be posi-
tioned to suit the thickness of the bundles. Also,
55 by having the plate 14 inclined downwardly to-
ward the frame 11, the bundles tend to slide
forward as the stock is withdrawn so that, after
the operator has placed a plurality of bundles
on the reel, and welded the ends of stock to-
gether, as aforesaid, the reel will require very
60 little attention until it becomes necessary to sup-
ply additional bundles.

While I have illustrated and described what
I now consider to be the preferred form of my
invention, it is apparent that various details
thereof may be changed without departing from
the spirit of the invention as defined in the ap- 5
pended claims.

Having thus described my invention, I claim:

1. In a reel for unwinding strand material, a
supporting frame having a generally upright ring
portion, a wheel-like member having an open- 10
ing for withdrawal of strand material there-
through, bearing means peripherally supporting
said member and mounting the same for rotation
adjacent the front of the opening of said ring
portion, a shaft mounted on said member and 15
projecting rearwardly therefrom substantially on
the axis of rotation thereof, a drum extending
rearwardly from said member and mounted for
rotation on said shaft, and means for non-ro-
tatably supporting coiled strand material in sur- 20
rounding relation to said drum.

2. In a reel for unwinding strand material, a
supporting frame having a generally upright ring
portion, a wheel-like member having an open- 25
ing for withdrawal of strand material there-
through, bearing means peripherally supporting
said member and mounting the same for rotation
adjacent the front of the opening of said
ring portion, a shaft mounted on said member 30
and projecting rearwardly therefrom substan-
tially on the axis of rotation thereof, a drum
extending rearwardly from said member and
mounted for rotation on said shaft, and means
for non-rotatably supporting coiled strand ma- 35
terial to be unwound, the last mentioned means
comprising a coil-receiving plate connected with
the frame and extending rearwardly and up-
wardly beneath said drum, a pair of laterally
spaced rails connected with the frame and ex- 40
tending rearwardly therefrom on opposite sides
of the drum so as to receive the coil or coils
therebetween, and a coil rest extending between
said rails rearwardly of said drum.

3. In a reeling apparatus, a frame having a
generally upright ring portion, a wheel-like 45
member having an opening therethrough for the
passage of strand material, a shaft projecting
rearwardly from said wheel-like member substan-
tially centrally thereof, a drum journaled for ro-
tation on said shaft, means for supporting a coil 50
of strand material in surrounding relation to
the drum, said ring portion of the frame having
an annular recess therein and said wheel-like
member having a rim portion extending into said
recess, rollers at spaced points on said rim por- 55
tion and operable in said recess for rotatably
mounting said wheel-like member, and an annu-
lar packing between the wheel-like member and
the ring portion of said frame.
